DENTAL EQUIPMENT STAND

Norman Horowitz, New York, N.Y. (107—21 Queens Blvd., Forest Hills, Queens, N.Y.), and Philip Spigner, New York, N.Y. (1460 Park St., Atlantic Beach, N.Y.)

Filed Dec. 21, 1962, Ser. No. 72,920

Term of patent 14 years

(Cl. D24—1)

FIG. 1 is a perspective view of the top, front and left side of a dental equipment stand showing our new design; and

FIG. 2 is an elevational view of the right side thereof. The undisclosed rear and bottom portions of the claimed article here plain and unornamented.

We claim:

The ornamental design for a dental equipment stand, as shown and described.
